PROCESS FOR THE "INDIRECT" OXIDATION-SPLITTING OF ACETYLENIC GAMMA-GLYCOLS

Abraham Brothman, Long Island City, N. Y.

No Drawing. Application November 6, 1948,
Serial No. 58,804

8 Claims. (Cl. 260—340.2)

1

My invention relates to a process for the "indirect" oxidation-splitting of acetylenic gamma-glycols to yield, immediately, products useful and convenient to the synthesis of alpha-hydroxy acids, the salts of alpha-hydroxy acids, the lactides of alpha-hydroxy acids, and the esters of alpha-hydroxy acids.

Acetylenic gamma-glycols have heretofore been subjected to oxidation-splitting by a variety of means, including:

I. The "direct" oxidation of acetylenic gamma-glycols by such materials as acid-potassium permanganate systems; alkaline potassium permanganate systems; acid-dichromate salt systems; Fenton's Reagent (30% hydrogen peroxide solutions plus ferrous sulfate or copper sulfate as a catalyst); and non-aqueous hydrogen peroxide solutions in the presence of osmium tetroxide; all as per Equation 1 to yield alpha-hydroxy acids as the desired products of the reactions.

Ozonolyses of acetylenic gamma-glycols, resulting in the formation of the ozonide derivatives of the starting acetylenic gamma-glycols, followed by water-promoted decomposition of the ozonides so obtained to yield alpha-hydroxy acids, have formed an important part of the work done on the "direct" oxidation-splitting of acetylenic gamma-glycols. Neither from the viewpoint of the chemical-physical properties and structure of ozone, nor from the standpoint of the reaction mechanics involved in achieving the oxidation-splitting phenomenon is ozone classifiable with the oxidation agents listed above in connection with the "direct" oxidation-splitting of acetylenic gamma-glycols. Yet, from an overall viewpoint, the use of ozone in the process sequence here described is entitled to listing under the general heading of the methods for promoting the "direct" oxidation-splitting of acetylenic gamma-glycols.

II. The "indirect" oxidation-splitting of acetylenic gamma-glycols via the oxidation-splitting of their di-ester derivatives under the influence of such agents as acid-potassium permanganate systems; alkaline potassium permanganate systems; acid-dichromate salt systems; Fenton's Reagent; and a variety of other chemical oxidizing reagents, all as per Equation 2 to yield alpha-ester acids as the desired products of the

reactions. In the instances reported in the literature, the di-acetate ester has been the one most frequently employed in these operations.

III. The "indirect" oxidation of acetylenic gamma-glycols via the oxidation-splitting of their ether derivatives by such agents as acid-potassium permanganate systems; alkaline potassium permanganate systems; acid-dichromate salt systems; Fenton's Reagent; and other chemical oxidizing agents, all as per Equation 3 to yield alpha-alkoxy acids as the desired products of the reactions.

Having thus stated the nature of the prior art as regards the "direct" and the "indirect" methods of accomplishing the oxidation-splitting of acetylenic gamma-glycols, it is both proper and pertinent to devote a few brief critical comments to the accomplishments of the prior art.

The "direct" oxidation-splitting of acetylenic gamma-glycols as outlined under item I is, in all instances, attended by extremely poor yields. These poor yields have been attributed to (1) the extreme lability of the hydroxyl positions on acetylenic gamma-glycols to oxidation, thus paving the road to the promotion of such side-reactions as the formation of acetylenic gamma-diketo compounds, and the formation of oxalic acid and other products attendant upon the further oxidation of acetylenic gamma-diketo compounds; and (2), the susceptibility of the alpha-hydroxy acid products of the oxidation-splitting reaction themselves to decomposition through oxidation. In any case, the poor yields by which the "direct" oxidation of acetylenic gamma-glycols have been characterized, combined with the high cost of the reagents employed in promoting these reactions, have re-

sulted in the infrequent commercial application of these methods.

While the methods generally outlined under item II have exhibited admirable yields as regards the achievement of the oxidation-splitting operation, the high cost of the oxidation reagents employed in this connection has, to date, restricted the uses of the general technique of oxidation-splitting of acetylenic gamma-glycols to comparatively few commercial applications.

The methods listed under item III above, like those included under item II, are generally endowed with high reaction efficiency characteristics. In this case, however, the restricted use of the methods falling under item III is attributable not only to the high cost of the oxidation reagents employed, but also to the limited versatility of the alpha-alkoxy acids thus produced as regards their conversion to other chemically useful materials.

In the equations given above, the symbol R in any given formula is to be taken to mean either a hydrogen atom or an alkyl radical. The symbol R' is to be understood to mean an alkyl radical exclusively. The use of numerical subscripts in connection with any of the formulae given herein is intended to generalize the equations for the instances where non-symmetrical acetylenic gamma-glycols are encountered. The asymmetry may consist of different alkyl radicals on both sides of the carbon linked to the acetylenic group; or, the asymmetry may involve non-identical groups attached to the acetylenically-bound carbons; or, combinations of the above-mentioned circumstances. This system of notation is continued below.

Having thus reviewed the prior art, I now pass to a presentation of my invention as regards the oxidation-splitting of acetylenic gamma-glycols. The generalized description of my invention may be divided into three component parts:

A. A step in which the acetylenic gamma-glycols answering the generalized formula,

are reacted with pyroboric acid to create the di-borate ester derivative of the given glycol; while acetylenic gamma-glycols answering to the generalized formula,

are converted to their di-acetate ester derivatives.

B. A step in which the di-ester derivatives of the starting acetylenic gamma-glycols are subjected to oxidation-splitting via the treatment of the di-ester derivatives obtained as per item A with gaseous oxygen under the conditions of temperature which will be described below, employing either boric acid or phosphoric acid or silicic acid as the catalyst for this operation.

C. Individual procedures for the conversion of the immediate product of the oxidation-splitting operation to free alpha-hydroxy acids, the salts of alpha-hydroxy acids, the lactides of alpha-hydroxy acids, and the esters of alpha-hydroxy acids.

The function served by the step in which the starting acetylenic gamma-glycol is converted to one or the other of the above-mentioned di-

ester derivatives thereof is to localize the oxidation reaction and to render it specific to the oxidation of the triple-bond.

There are many satisfactory methods by which the respective di-ester derivatives mentioned above may be prepared.

Thus the di-acetoxy ester may be obtained by (1) the reaction of an acetylenic gamma-glycol with acetic anhydride in the presence of sodium acetate; (2) the reaction of ketene with an acetylenic gamma-glycol; and (3) the direct reaction of an acetylenic gamma-glycol with glacial acetic acid in the presence of a third component such as xylol, in which process sequence the xylol serves to effect the pseudo-azeotropic distillation of the water-of-reaction.

Where the di-borate ester of an acetylenic gamma-glycol is desired, again it is possible to use any of a number of satisfactory techniques. These may include (1) a direct reaction between boric anhydride and the acetylenic gamma-glycol, in the presence of a solvent where the demands of temperature control impose the requirement of good agitation of the reaction system and the reactants-mixture per se does not possess the desired fluid properties; (2) a direct reaction between the acetylenic gamma-glycol and pyroboric acid, sometimes in the presence of a solvent for the reasons cited in the previous technique; and (3) a reaction between the acetylenic gamma-glycol and boric acid in the presence of a third and inert solvent such as toluol or xylol under the conditions of a pseudo-azeotropic distillation of the water from the reaction system.

In the preferred embodiment of my invention, the di-acetoxy derivatives of acetylenic gamma-glycols are prepared by the action of acetic anhydride on the acetylenic gamma-glycols under the influence of sodium acetate as a catalyst at a temperature for the reaction ranging between 80° C. and 140° C., depending upon the glycol at hand and its stability characteristics in the presence of acetic acid and acetic anhydride itself. The resultant reaction system is then subjected to a fractionation operation for the purposes of isolating the di-acetoxy derivative of the acetylenic gamma-glycol.

In the preferred embodiment of my invention, where the di-borate ester of an acetylenic gamma-glycol is prepared, the given gamma-glycol is dissolved in a solvent such as benzene, toluene, or xylol and is reacted with pyroboric acid under the conditions of a gradual addition of the pyroboric acid powder to the solution of the acetylenic gamma-glycol, while maintaining vigorous agitation and a reaction temperature lying in the range between 30° C. and 100° C.

The detailed procedures implicit in the aforementioned preferred methods for the preparation, respectively, of the di-acetoxy and the di-borate ester derivatives of acetylenic gamma-glycols, and the unit operations which connect these steps with the subsequent steps of my invention are set forth generally in the illustrative examples appearing later herein.

Where the oxidation-splitting operation is carried out on the di-borate ester derivative of an acetylenic gamma-glycol, no measures are employed for the isolation of the ester other than the removal of the solvent medium in which the reaction was executed. This is carried out under such vacuum conditions that at no time during the removal of the solvent medium by the vacuum 75 stripping operation is a temperature of 80° C.

exceeded. When in accordance with the rule set down above, the di-acetoxy derivative of an acetylenic glycol is employed, the di-ester is isolated from the reaction mass for the best results.

Where the di-borate ester derivative of an acetylenic glycol is to be subjected to an oxidation-splitting operation, the boric acid by-product of the borate ester formation, where boric anhydride or pyroboric acid are employed in the di-ester synthesis, or the excess of boric acid used in the third-named method above, may be utilized as the catalyst for the oxidation-splitting operation. Where the di-acetoxy derivative of an acetylenic glycol is to be processed, between one and fifteen percent of 100% phosphoric acid, based on the weight of di-ester being processed, is added to the di-acetoxy derivative.

Employing vigorous agitation for the reaction mass, the temperature of the reaction mass is raised, depending upon the specific characteristics of the di-ester which is being processed, to a temperature ranging between 80° C. and 200° C., prior to the initiation of oxygen passage through the reaction mass. A quantity lying in the range of from one and one-quarter to two and one-half times the stoichiometric requirement of oxygen, according to Equations 4 and 5, or 9 and 10, is passed through the reaction mass in the presence of agitation sufficient to cause the fine-size distribution of the gas bubbles throughout the reaction mass. The period of time for oxygen input may range between four and twenty-four hours, depending upon the particular acetylenic gamma-di-ester being processed.

Equations 4 through 8 and Equations 9 through 13 illustrate the supposed mechanics of the reaction involved in the oxidation-splitting phenomenon as accomplished by my invention. In both these sets of equations, for the sake of simplicity and convenience of presentation of the ideas projected therein, I have illustrated the oxidation-splitting phenomenon on completely symmetrical acetylenic gamma-di-ester compounds. The extension of the views presented in this connection to various instances of non-symmetrical acetylenic gamma-di-ester compounds will be immediately apparent to those learned in the art.

According to the best information available to me as a result of my researches, the mechanics of the reactions which take place under the influence of oxygen passage through the reaction mass are those set forth under Equations 4 through 8 for the case of the di-acetoxy compounds, and Equations 9 through 13 for the case of the di-borate compounds.

In other words, the evidence collected by me during my research tends, in the instances of Equations 4 through 8, to imply that under the influence of the di-radical represented by molecular oxygen, one of the three sets of electron-pairs shared between the acetylenically-bound carbon members is "impaired," creating a corresponding di-radical. From this situation, the addition of the molecular oxygen to form a peroxide, which later rearranges itself to a di-keto form, may be visualized. This entire concept is projected in Equation 4. According to Equation 5, the reaction between oxygen and phosphoric acid to yield a peroxide radical and a di-hydrogen phosphate radical is postulated. The splitting of the di-keto form under the influence of the peroxide and the di-hydrogen phosphate radicals to form an organic peroxide and the indicated di-hydrogen phosphate compound would, it is reasonable to believe, be the next step. This view is presented in Equation 6.

The reaction set forth under Equation 7, between the di-keto derivative of the starting di-acetoxy acetylenic compound and the organic peroxide arising as a consequence of Equation 6 leading to the formation of the acid anhydride of the expected alpha-acetoxy acid and a molecule of alpha-acetoxy acid follows, if not specifi-

cally then generally, from the modern knowledge of the action of alkyl peroxides in related reactions. The reaction projected in Equation 8 between the alpha-acetoxy acid (produced in accordance with Equation 7) with the di-hydrogen phosphate compound (produced according to Equation 6) in which the regeneration of the acid catalyst and the yielding of another molecule of the acid anhydride is presented, flows quite logically from the previous development of the probable reaction mechanics involved in the oxidation-splitting phenomenon as accomplished by me.

In Equations 9 through 13, the probable reaction mechanics involved in the oxidation-splitting of acetylenic gamma-di-borate esters is projected for the case where boric acid is employed as the oxidation-splitting catalyst.

In other words, in both instances the direct product of the reaction between the di-esters set forth above and oxygen, under the conditions generally described above, is an alpha-ester acid anhydride.

The third phase of my invention, namely, the methods by which I convert the alpha-acetoxy acid anhydride or the alpha-borate acid anhydride which I obtain as the direct product of the oxidation-splitting operation to the various end products listed by me in the statement of my invention, in each case involves the transformation of the alpha-ester anhydride to the lactide of the homologous alpha-hydroxy acids to which they are related. The conversion of alpha-acetoxy acid anhydrides to the indicated lactide forms is accomplished in the following manner:

To the reaction mass resulting from the performance of the oxidation-splitting operation on the di-acetoxy ester derivative of an acetylenic gamma-glycol, one adds approximately one and one-quarter times the stoichiometric requirement of water to decompose the anhydride, and thereby yield the free alpha-acetoxy acid. This reaction is illustrated in Equation 14.

This reaction is usually instantaneous, even when conducted at atmospheric temperatures.

The transformation of the thus obtained free alpha-acetoxy acid to the lactide of the homologous alpha-hydroxy acid is then accomplished by the reaction as set forth in Equation 15:

The reaction mass resulting from the operation in Equation 14 is then transferred to a reactor flask provided with agitation and equipped with a Bidwell-Sterling adapter which connects the reactor flask with a vertical condenser. To the reaction mass present in the reactor flask, there is added that quantity of xylol or toluol which is consistent with maintaining the highest possible temperature for the ensuing refluxing operation which avoids the serious inception of

the side-reactions set forth under Equations 16 and 17:

(Where R' is an alkyl group)

The reaction set forth in Equation 16, which consists of the splitting out of a molecule of acetic acid from the structure of the alpha-acetoxy acid to yield an unsaturated derivative acid, is a phenomenon with an energy-of-activation which depends on the particular alpha-acetoxy acid being processed. The temperatures, therefore, at which this phenomenon will take place for a given alpha-acetoxy acid is peculiar to that alpha-acetoxy acid. The degradation reaction set forth under Equation 17 similarly shows a variation from lactide to lactide; and, consequently, no maximum temperature range can be specified for the lactide formation reaction which would broadly hold for all lactides.

The receptacle portion of the Bidwell-Sterling adapter is then filled with such a quantity of xylol or toluol that the dropping of condensate from the vertical condenser causes an overflow of xylol from the receptacle portion of the adapter to the reactor flask. Maintaining vigorous agitation, one is able to maintain the reaction mass in the flask under reflux conditions. The toluol- or xylol-acetic acid-water distillate from the flask passes from the reactor flask to the vertical condenser, where it is condensed and dropped to the receptacle portion of the Bidwell-Sterling adapter. The water-acetic acid mixture settles to the bottom of the Bidwell-Sterling adapter receptacle, while the xylol component of the distillate becomes an upper layer. The receptacle portion of the Bidwell-Sterling adapter is tapped at such intervals as assures the maintaining of the originally stipulated maximum reaction temperature. This operation is continued until no further acetic acid is taken over. The lactide of the homologous alpha-hydroxy acid to the starting alpha-acetoxy acid will then be found in solution in xylol in the reactor flask. The xylol is then driven off, generally under vacuum stripping conditions, to obtain the crude lactide product. The formation of the lactide from the alpha-acetoxy acid starting reactant is carried out in the presence of the phosphoric acid present in the reaction mass as a result of its original incorporation in the oxidation-splitting phase of my invention. The phosphoric acid acts, in the case of the lactide formation, again in the role of a catalyst.

The conversion of alpha-borate acid anhydrides, where these are involved in my invention, to the lactides of their homologous alpha-hydroxy acid forms is, with the exception of a few elements of detailed procedure, accomplished by the same general methods mentioned above in connection with the conversion of alpha-acetoxy acid anhydrides to lactides.

The procedures, and the reactions involved, where they differ from the instances provided by

the above-described conversion of alpha-acetoxy acid anhydrides to lactides, is detailed below.

From Equation 18, one finds:

it will be observed that the treatment of the alpha-borate acid anhydride with water results not only in the conversion to the free acid form, but also in the hydrolysis of the borate group to yield two mols of the alpha-hydroxy acid shown on the right-hand side of Equation 18.

Depending upon the lability of the so-produced alpha-hydroxy acids to destruction through the formation of the powerful acids resulting from the phenomenon set forth under Equation 19,

cooling of the reaction mass during the water-promoted decomposition of the alpha-borate acid anhydride may become necessary. Since alpha-hydroxy acids vary in their lability to the conditions invoked by the formation of the complex set forth under Equation 19, it is not possible to prescribe hard and fast rules regarding the temperatures which must be maintained during the water-promoted decomposition reaction.

Since boric acid is present in the reaction mass resulting from the hydrolysis operation in sharp excess over the stoichiometric requirements of Equation 19, the reaction to produce the complex set forth under Equation 19 is rather complete. The formation of the lactide of the alpha-hydroxy acid produced in accordance with Equation 20 therefore presupposes the destruction of the complex. The destruction of the complex is accomplished by the reacting of the mixture resulting from the addition of a slurry of calcium hydroxide to the reaction mass resulting from the hydrolysis operation.

Since the reaction mass

A 20% slurry of calcium hydroxide, providing calcium hydroxide in sharp excess of the stoichiometric relationships involved in Equation 21, is employed for this operation.

(21)

The reaction is generally carried out in a temperature range lying between 20° C. and 60° C., depending upon the particular lactide being formed. The reaction indicated under Equation 21 is complete within one to two hours of the treatment prescribed, depending upon the particular complex being processed. The high water-solubility of the calcium salts of the most important alpha-hydroxy acids, provides the

basis for the separation of the calcium salt of the alpha-hydroxy acid from the excess of calcium hydroxide employed and the calcium borate by-product formed in the decomposition of the complex.

The reaction product is then subjected to a filtration operation, following which the calcium salt of the alpha-hydroxy acid will be found in solution in the filtrate. The calcium borate resulting from the above-mentioned filtration operation may be treated with 36% hydrochloric acid at room temperatures to recover the originally employed boric acid for re-use. The filtrate, containing the calcium salt of the alpha-hydroxy acid, is acidulated at room temperature with any reasonable excess over stoichiometric requirement of phosphoric acid to yield the free alpha-hydroxy acid plus calcium phosphate. Excesses of phosphoric acid in the order of 5% to 10% of the expected yield of lactide, will give the best results.

The thus processed filtrate is then subjected to treatment in an apparatus set-up completely identical to that described for the conversion of the alpha-acetoxy acids to lactides above, the temperature for the refluxing operation in this case being guided by the maximum temperature which is consistent with the elimination of the degradation reaction set forth under Equation 22.

The crude lactides which are thus obtained by each of the sets of operations described above may be isolated in pure form from their accompanying impurities by extraction of the final residues in the reactor flask members of the above-described standard laboratory equipment set-ups with such solvents as diethyl ether, after which the pure lactide is obtained by vacuum evaporation of the ether solvent.

The conversion of the crude lactides, or the purified lactides (whichever may prove to be more convenient in any given instance) to the esters of alpha-hydroxy acids (by the well-known processes of transesterification), to free alpha-hydroxy acids (by the conversion of the lactide to a salt of the alpha-hydroxy acids by a saponification action, followed by an acidulation of the salt and an extraction of the free alpha-hydroxy acid thus obtained), and to the salts of alpha-hydroxy acids (by the saponification of the lactide) are procedures well-known to those learned in the art.

Those skilled in the art will readily appreciate that the broad ranges of processing conditions which I have set forth above flow from the broad scope of applicability of my invention. I have, however, in each important processing condition, given the principles which guide the selection of the optimum conditions for the carrying out of any specific application of my invention.

The advantages offered by my invention over the prior art are the following:

1. In contradistinction to all methods previously offered for the "direct" and/or "indirect" oxidation-splitting of acetylenic gamma-glycols, the use of the methods proposed by my invention offers a generally higher range of reaction efficiencies. Reaction efficiencies varying from 60% to 95% of theoretical yield of the lactide forms

described above will be obtained when optimum conditions are observed, depending upon the particular acetylenic gamma-glycol being processed.

2. In contradistinction to all methods previously proposed in the prior art for the oxidation-splitting of acetylenic gamma-glycols, regardless of whether these means have been of the "direct" or "indirect" type, the reagent material used in my invention, namely oxygen, will demonstrate a greater applicability commercially to the extent that gaseous oxygen is available at a lower cost than are any of the oxidation agents previously employed in the prior art. Taken into account with this factor, one must also consider the fact that the weight of oxygen demanded per unit of end-product lactide realized is lower than the weight of any of the oxidation reagents prescribed in the prior art per unit of final product achieved on a purely theoretical basis. Combining this factor with the higher yield efficiencies achieved by me and the lower excesses of oxidation reagents required by me over those recommended by the prior art in the instances of the various oxidation agents employed by them, the oxidation-splitting of acetylenic gamma-glycols becomes an economically feasible operation in the synthesis of many low-cost and useful chemicals.

3. When the oxidation-splitting operation is performed on the di-borate ester derivative of the acetylenic gamma-glycol (in instances where I propose the use of the di-borate ester of the starting acetylenic gamma-glycol), my invention offers the particular advantages that the synthesis of free alpha-hydroxy acids, their salts, their esters, and their lactides are placed within range of simple preparation without entailing a high cost of reagent materials in the preparation of a suitable di-ester for the oxidation-splitting operation. This follows from the above-mentioned technique for the recovery of the boric acid side-product of the alpha-borate acid anhydride hydrolysis, and the technique which is proposed in my second illustrative example for the preparation of pyroboric acid.

4. The fact that the alpha-acid anhydride intermediate product present in the reaction mass at the end of the oxidation-splitting operation may, by the procedures recommended above, be converted to the lactide of the respective expected alpha-hydroxy acid final product lends the syntheses proposed by me to the easy, rapid, and efficient achievement of the esters and the calcium, sodium, and other salt derivatives of alpha-hydroxy acids.

Undoubtedly those skilled in the art will be capable of introducing many variants on the techniques proposed by me. Instances of such possible variations of the procedures I propose include the following:

a. The use of di-ester derivatives, other than the di-acetoxy derivative of the acetylenic gamma-glycol, in instances where the use of the di-acetoxy ester derivative is proposed, such as the di-propionoxy, etc., ester derivatives of any given acetylenic gamma-glycol. In this regard, the general purposes for which the di-acetoxy ester derivative of the starting acetylenic gamma-glycol is used in connection with my methods of oxidation-splitting of the acetylenic triple-bond is the vital factor, rather than the particular form of the di-ester derivative employed.

b. In instances where the di-borate ester derivative of a starting acetylenic gamma-glycol is employed, it is possible to substitute other in-

organic ester derivatives such as the di-phosphate, the di-bisulfate, etc., ester derivatives. Here again, the main purposes served by the creation of the di-borate ester derivative which include the protection of the hydroxyl stations against direct oxidation, the obtaining of an alpha-ester product which will resist oxidation, and the achievement of a form which will be susceptible to immediate direct hydrolysis is the underlying principle involved.

c. Relative to the particular di-ester derivative of the starting acetylenic gamma-glycol employed, it is possible that in given instances, higher degrees of protection of the basic acetylenic gamma-glycol structure against degradation to di-vinyl acetylene structures may be obtained from the use of one di-ester derivative over another. Similarly, and following from this consideration, it is possible that the achieving of the additional protection of the basic acetylenic gamma-glycol structure from the side-reaction tendencies mentioned above may lend itself towards the use of higher temperatures for the oxidation-splitting operation, thereby permitting a more rapid achievement of the oxidation-splitting operation.

Since many possibilities are presented for the conversion of the immediate product of the oxidation-splitting operation as performed by my invention to the salts of alpha-hydroxy acids, free alpha-hydroxy acids, and the esters of alpha-hydroxy acids, it should be underscored that the methods of converting the alpha-ester acid anhydrides which my method of performing the oxidation-splitting operation achieves, to the mentioned products which I propose, are illustrative rather than specific to the general invention here outlined.

Relative to the use of oxygen as the oxidizing agent, it is also possible, by sacrificing speed of reaction, to employ air in the place of the oxygen specified by me.

The following are illustrative examples of the application of my invention to the oxidation-splitting of acetylenic gamma-glycols to yield alpha-ester acid anhydrides as the direct product of the oxidation-splitting operation, with the indicated potentialities for conversion of the acid anhydride to the free alpha-hydroxy acids, the lactides of the free alpha-hydroxy acids, the salts of the free alpha-hydroxy acids, and the esters of the free alpha-hydroxy acids.

Example 1.—The synthesis of the lactide of lactic acid from 2,5-diol hexine-3

To a flask provided with agitation and connected by way of a Bidwell-Sterling adapter to a vertically mounted water-cooled condenser, 175 g. of boric acid and 1,350 cc. of xylol are added. The flask is then heated until reflux conditions are established. Vapors of xylol and water pass to the vertically mounted condenser, where they are condensed and dropped to the receptacle portion of the Bidwell-Sterling adapter. A collection of a two-phase distillate, of which the xylol is the upper layer and of which water is the lower layer, ensues. As the operation progresses, the receptacle portion of the Bidwell-Sterling adapter becomes filled with condensate, so that ultimately the continued passage of condensate to the receptacle causes the continuous overflow of the collected xylol upper layer to the flask. The receptacle portion of the adapter is tapped at sufficiently frequent intervals to guarantee a height of xylol layer in the receptacle consistent with

the overflow of cleanly separated xylol from the receptacle to the flask. When the amount of water collected from the continued performance of this operation reaches the magnitude of one and one-quarter mols of water per mol of boric acid originally charged to the system, the refluxing operation is halted and the mass in the flask is subjected to a filtration operation in which the pyroboric acid powder is separated from the xylol in which it is mechanically dispersed. Care must be taken during this operation to avoid contact of the so produced pyroboric acid filter cake with moist air. For this reason, the filter cake is not sucked dry, but is allowed to be wetted by entrained xylol. The pyroboric acid which is thus prepared is then added to a solution of 200 g. of 2,5-diol hexine-3 present in solution in 750 cc. of diethyl ether under the conditions of a vigorous agitation of the thus obtained reaction system and a constantly maintained reaction temperature of 30° C. The addition of the wetted pyroboric acid reagent should be performed in a gradual manner, to the end that the pyroboric acid is added at approximately the rate at which it is being reacted. The thus obtained reaction system is agitated for a period of one hour following the completion of the pyroboric acid addition, during which time the reaction mass temperature is still maintained at 30° C. At the conclusion of the mentioned period of agitation, the reaction solvent medium is stripped off under vacuum conditions, the solution having first been separated by a settling operation from all but a quantity of boric acid precipitate, amounting to approximately 5% of the expected yield of di-borate ester derivative. Having thus removed the solvent from the reaction system, the temperature of the di-borate ester derivative is raised to 110° C., and, maintaining the reaction mass temperature at 110° C. for the entire period of four and one-half hours, 91.5 l. of oxygen, referred to standard conditions, are passed into the solution over the allotted four and one-half hour reaction time. The reaction mass from the aforementioned processing procedure is then added to 40 cc. of water, while vigorously agitating the reaction system resulting from this addition. The alpha-borate acid anhydride, obtained from the oxidation-splitting operation, is added to the water at the maximum rate which is consistent with the continued maintaining of a temperature of 20° C., under the conditions of an ice-water bath cooling of the reaction flask, for the entire duration of the addition sequence. To the thus obtained reaction system, a slurry of 450 g. of calcium hydroxide in 1.8 l. of water is added. This operation is also carried out under the conditions of a constantly maintained reaction temperature of 20° C. The reaction mass resulting from this operation is filtered, and the filtrate from this operation is processed in the following manner:

A charge of 237 g. of 50% phosphoric acid is added to the filtrate, while maintaining a reaction temperature not in excess of 40° C. Adding a quantity of xylol consistent with maintaining a refluxing temperature not in excess of 135° C. as a maximum condition to the thus obtained aqueous solution of lactic acid, a pseudo-azeotropic distillation of water in an apparatus set-up completely identical to that described for the case of the conversion of boric acid to pyroboric acid is pursued until no further water is collected. The reaction mass then remaining in the reactor flask is taken up in diethyl ether, subjected to a filtration for the separation of all inorganic materials

from the ethereal solution of the product, is carefully separated from the phosphoric acid sediment which passes through the filter with the ethereal solution, and is then subjected to a vacuum stripping operation to relieve the final product of the ether. In this manner, a yield of 217 g. of the lactide of lactic acid, representing a yield efficiency of 86% on the basis of the theoretically expected yield from the starting acetylenic gamma-glycol, is obtained.

This material is suitable for the formation of methyl lactate and other esters of lactic acid, for conversion to the salts of lactic acid and for conversion to lactic acid itself.

Example. 2.—The synthesis of the lactide of alpha-hydroxy isobutyric acid from 2,5-diol 2,5-dimethyl hexine-3

To a reaction system consisting of 200 g. of 2,5-dimethyl 2,5-diol hexine-3 and 15 g. of anhydrous sodium acetate, there is gradually added, while the hexine-sodium acetate mixture is maintained at 105° C., 349 g. of acetic anhydride. The thus obtained reaction system is agitated at the same temperature for a period of two and one-half hours, at the conclusion of which the final reaction mass is subjected to a vacuum distillation operation to relieve the reaction mass of the acetic acid product of reaction and the excess of acetic anhydride originally employed. The thus "isolated" di-acetoxy derivative of 2,5-dimethyl 2,5-diol hexine-3 receives a charge of 20 g. of 100% phosphoric acid. The phosphoric acid-di-acetoxy ester is then subjected to an oxidation-splitting operation employing a uniformly maintained reaction temperature of 145° C. in the same manner as regards reaction time, conditions of agitation, and general manner of oxygen-input, as was described in Example 1. A quantity of oxygen amounting to 73.5 l. of oxygen, referred to standard conditions, is passed through the solution during the oxidation-splitting operation. The alpha-acetoxy acid anhydride resulting from this operation is then processed in the following manner:

To the acid anhydride, there is added 40 cc. of water, while a reaction temperature of 50° C. as a maximum is maintained. Employing a standard laboratory distillation set-up, in which the effluent from the top of the distillation column passes by way of a Bidwell-Sterling adapter to a vertically mounted water-cooled condenser and maintaining the receptacle portion of the Bidwell-Sterling adapter charged at all times with a small layer of water, a mixture of the decomposed acid anhydride and of toluol is subjected to refluxing under atmospheric pressure conditions. A sufficient amount of toluol is maintained in the reactor at all times, so that at no time during the progress of the lactide formation operation is a temperature of 135° C. exceeded. When no further acetic acid distills over from the reactor flask, the formation of the lactide of alpha-hydroxy isobutyric acid is complete. The isolation of the lactide in pure form again involves the taking up of the residue in the reactor flask in diethyl ether, the careful settling of the ethereal solution from the phosphoric acid sediment contained therein, and the final separation of the lactide by the vacuum stripping of the ether of solution under vacuum stripping conditions. In this manner, a yield of 221 g. of the lactide of alpha-hydroxy isobutyric acid, representing a yield efficiency of 90% on the basis of the theoretically expected yield from

15

2,5-dimethyl 2,5-diol hexine-3 is obtained. The lactide in this instance is also capable of conversion to the methyl and other esters of alpha-hydroxy acid via a transesterification operation, and, by the same sequence of procedures as is proposed, of conversion to the salts of alpha-hydroxy isobutyric acid and free alpha-hydroxy isobutyric acid itself.

I claim:

1. In the indirect oxidation-splitting of acetylenic gamma-glycols in which an acetylenic gamma-glycol is converted to the corresponding di-ester and subjected to an oxidation-splitting operation, the improvement comprising incorporating an oxidation catalyst selected from the group consisting of phosphoric acid, boric acid, and silicic acid in the di-ester of the gamma-glycol, introducing gaseous oxygen into the resulting mixture and thereby oxidizing the di-ester at the point of the acetylenic linkage and splitting the di-ester at said point, and mixing the resulting product with water to hydrolyze the resulting reaction product.

2. The process as claimed in claim 1 characterized in that the di-ester is oxidized at a temperature of from 80° to 200° C.

3. The process as claimed in claim 1 characterized in that said resulting reaction product is hydrolyzed at a temperature of from about 20° to 60° C.

4. The process as claimed in claim 1 characterized in that the hydrolyzing operation is effected in the presence of the oxidation catalyst, thereby producing a lactide having the same number of carbon atoms as the acetylenic gamma-glycol.

5. The process as claimed in claim 1 characterized in that the di-ester is an ester of an aliphatic acid.

6. The process of producing lactide products from organic di-esters of acetylenic gamma-glycols, comprising the steps of oxidizing a di-ester

16

of an acetylenic gamma-glycol with gaseous oxygen in the presence of an oxidation catalyst selected from the group consisting of phosphoric acid, boric acid, and silicic acid at a temperature of from 80° to 200° C., thereby converting the di-ester to the corresponding alpha-ester acid anhydride, mixing the anhydride product with water to effect hydrolyzation thereof, mixing the water and anhydride at a temperature substantially below the oxidation temperature, azeotropically distilling off the water and regenerated organic acid from the hydrolyzed mixture in the presence of the oxidation catalyst, and thereafter separating the lactide product from the catalyst.

15. 7. The process as claimed in claim 6 characterized in that the di-ester is an ester of acetic acid.

8. A process for the "indirect" oxidation-splitting of symmetrical acetylenic gamma-glycols for the production of lactides of alpha-hydroxy acids, 20 which comprises converting an acetylenic gamma-glycol to an acetylenic gamma-di-ester derivative thereof, heating the resulting acetylenic gamma-di-ester derivative with substantially pure oxygen gas in the presence of phosphoric acid as an oxidation catalyst and oxidizing said derivative to split the di-ester derivative and produce an alpha-ester acid anhydride product mixture, reacting the said product mixture containing the phosphoric acid with water and thereby 25 converting the product to the alpha-ester acid derivative, thereafter refluxing the resulting mixture in the presence of water thereby converting said last-mentioned derivative to a lactide, and recovering the resulting lactide product.

35. ABRAHAM BROTHMAN.
